UNITED STATES PATENT OFFICE

137,406

DESIGN FOR A BROOCH OR SIMILAR ARTICLE

Dora E. Chesebro, Nevada City, Calif.

Application November 10, 1943, Serial No. 111,638

Term of patent 3½ years

To all whom it may concern:

Be it known that I, Dora E. Chesebro, a citizen of the United States, residing at Nevada City, in the country of Nevada and State of California, have invented a new, original, and ornamental Design for a Brooch or Similar Article, of which the following is a specification, reference being had to the accompanying drawing, forming part thereof.

I claim:

The ornamental design for a brooch or similar article, as shown.

DORA E. CHESEBRO.
